UNITED STATES PATENT OFFICE.

CHARLES WILFRED BIRKIN, OF NOTTINGHAM, ENGLAND.

DESIGN FOR LEVERS LACE.

No. 38,195.

Specification for Design.

Patented Aug. 28, 1906.

Application filed July 18, 1906. Serial No. 326,798. Term of patent 3½ years.

To all whom it may concern:

Be it known that I, CHARLES WILFRED BIRKIN, a subject of the King of Great Britain and Ireland, residing at Nottingham, county of Nottingham, England, have invented a new, original, and ornamental Design for Levers Lace, of which the following is a specification, reference being had to the accompanying drawing, forming a part thereof.

The figure is a plan view of Levers lace, showing my new design.

I claim—

The ornamental design for Levers lace as shown.

CHARLES WILFRED BIRKIN.
